HOLDER FOR FIRE EXTINGUISHERS

Daniel Krakauer, Brooklyn, N. Y., assignor to
 Kay Manufacturing Corporation, Brooklyn,
 N. Y., a corporation of New York

Application December 23, 1942, Serial No. 469,905

7 Claims. (Cl. 248—313)

This invention relates to holders for fire extinguishers and particularly to the type which is quickly and easily releasable by unskilled persons or in the excitement of an emergency.

Present holders for such extinguishers not only necessitate the use of an excessive amount of metal, now scarce, but do not hold with sufficient firmness and thereby permit the extinguisher to rattle or move slightly in various directions, especially in combat vehicles or vessels such as tanks, warships and the like where vibrations, shock and impact are to be expected in normal operation.

The invention therefore contemplates the provision of an economical holder, employing a minimum amount of material and made largely of wire, which, while holding the extinguisher firmly against movement under the stresses of vibration, shock and impact, is so constructed that the extinguisher is readily and quickly removable from the holder by the natural action to be expected of an excited person in emergencies.

The various objects of the invention will be clear from the description which follows and from the drawing, in which,

Fig. 1 is a side view of the holder as it appears when secured to a wall, showing the extinguisher held thereby.

Fig. 2 is a front view of the same, part of the extinguisher being omitted to expose the holder to view.

Fig. 3 is a fragmentary enlarged perspective view of a modified form of the upper spring portion or top of the holder.

Fig. 4 is a fragmentary side view of a modified of the lower part of the holder, showing the extinguisher in dash-dot lines.

Figs. 5 and 6 are similar views of other modified forms of the same.

In the practical embodiment of the invention shown by way of example, the holder, designated generally by the numeral 10, is made preferably of a single piece or length of wire, and is preferably formed symmetrically about its longitudinal center line. Spacing clips or braces as 11, 12 and 13 arranged at suitable intervals and preferably at bends in the wire, connect the long upright sides of the holder and prevent relative longitudinal and transverse movement of said sides. Each clip is preferably made of sheet metal having its end edge portions 14 bent into cylindrical form and wrapped around the wire of the holder sides, and has a flat connecting portion 15 pierced as by the holes 16, 17 for the passage therethrough of suitable fastening means

such as the screws 18 (Fig. 1) into the wall 19 or other supporting surface.

The wire of which the holder is made is of sufficient diameter and of the proper material to give the spring action later to be described and to impart the desired strength and holding action to the wire. As shown in Figs. 1 and 2, the ends of the wire at the bottom of the holder are turned upwardly and held by the clip 20 to form the upstanding lip 21 adapted to engage the lower front of the extinguisher 22 thereby to aid in preventing movement of the extinguisher away from the wall 19. However, the bottom 23 of the holder may be formed in various ways depending in part on the type of nipple 24 on the extinguisher.

As shown in Figs. 1 and 2, each of the two spaced side elements of the bottom 23 extending rearwardly from the lip 21 is curved convexly upwardly to engage and press upon the concave bottom surface 25 of the extinguisher. The side elements of the holder bottom being held in transverse spaced relation by the clip 11, it will be seen that said elements are sufficiently spaced apart to receive the nipple 24 between them. The bottom 23 of the holder prevents the extinguisher nipple from being withdrawn transversely from the holder, whether the lip 21 is present or not by reason of the spring pressure exerted thereby upon the bottom of the extinguisher. In other words, the bottom 23 serves as a spring owing to its shape and position and to the bend 26 which connects it to the holder sides 27, 28. The distance between the top 29 of the holder and said bottom 23 is preferably less than the length of the extinguisher to obtain the aforesaid spring action.

While the wire sides of the holder are preferably upright generally, they need not be precisely parallel either throughout or at the various sections thereof, but may be made convergent or divergent as may be found convenient, being preferably somewhat convergent at the bends 35 for the purpose later to be described. As shown at 45 the portion 32, between the upper narrower portion 30 of the sides and the lower similarly narrower portion 31, the sides are preferably, though not necessarily, transversely spaced apart a somewhat greater distance than at the remainder of the rear part of the holder to give a greater bearing area against the supporting wall or surface. Suitable reversely curved bends as 33, 34 join the side portions 32 to the portions 30 and 31.

The top 29 of the holder cooperates with the

bottom 23 to press the extinguisher therebetween with considerable force because of the spring action of said top and bottom. The extinguisher is thereby adequately held against vibration or movement in any direction. Additional points of contact between the holder and extinguisher are additional precautions against possible vibration or rattling under the most adverse conditions. Such points are the lip 21 which contacts with the front lower part of the extinguisher, the clips 11, 12 and 13, the cylindrical portions of which contact the back part of the extinguisher, and the spring bends 35 which may squeeze between them the flat parts 36 of the bearing or stuffing box for the plunger rod 37 of the extinguisher. Said bends are transversely spaced apart the correct distance to effect this purpose, the distance being preferably less than the distance between the flat faces 36, and the bends preferably converging toward each other as has been previously mentioned. Said bends 35 are closed at the front thereof, the lower branch of each bend being joined to the corresponding upright side of the section or portion 39 by the inclined part 38, and the upper branch extending substantially horizontally and rearwardly. The upright part 39 connects the upper branch to the forwardly extending top 29.

Said top may be formed in somewhat different shapes depending on whether the ends of the one piece length of wire are arranged at the top (Fig. 3) or elsewhere. As shown in Figs. 1 and 2, the wire ends being arranged at the lip 21 and there joined at the bottom of the holder, the spaced side elements of the top 29 are integrally joined by the transverse part 40 at the ends of the upwardly and forwardly inclined parts 41. A downwardly extending indent 42 is formed in the top 29 intermediate its front and rear in such position that it is in the path of the handle 43 of the extinguisher when the extinguisher is in a forwardly inclined position with its bottom resting on the holder bottom 23. Consequently, when the handle 43 is pressed rearwardly toward the wall 19, it engages the indent 42 and raises the top 29 against the downward spring pressure thereof and snaps past the indent into the position of Figs. 1 and 2. The distance between the top and bottom of the holder being normally less than the corresponding length of the extinguisher, the resulting spring pressure of the top and bottom of the holder when the extinguisher is forced therebetween upon the corresponding parts of the extinguisher is considerable and enough, as has been indicated, to maintain the extinguisher in place under severe conditions against vibration or relative movement of any kind, aided by the bends 35 and the spacing clips. To remove the extinguisher in the easiest way, the front end of the top 29 is slightly lifted, as it easily can be by reason of the length of the upper part of the holder and the bends therein and the consequent obtainable leverage and yieldability of the top, and the extinguisher is tilted forwardly out of the holder. However, in case of confusion or excitement, if the user fails to lift the top as described, a forward pull on any portion of the upper part of the holder, which is the natural way in which one would grasp the extinguisher for removal thereof, will carry the handle 43 forwardly past the indent 42 to tilt the extinguisher out of the holder, the top 29 yielding upwardly under such forward pull.

In the form shown in Fig. 3, each of the side

elements of the top 45 terminates in a loop 46 providing a depressed part 47 serving the same purpose as the indent 42. In this case, a clip 48 similar to the clips 11, 12 and 13 joins the upright portions 39 near the bends 35 to prevent relative transverse movement of the end loops.

Modified forms of the bottom of the holder are shown in Figs. 4, 5 and 6, these forms being adapted for use with extinguishers 22 having discharge nipples differing in length. As shown in Fig. 4 instead of arranging the ends of the one piece length of wire at the lower end of the holder, they may be arranged elsewhere, as at the top (Fig. 3), or at any point of the sides in the cylinder 14 of one of the braces or clips 11, 12 or 13. The transverse part 50 joins the upwardly convex spaced side elements 51 of the bottom 52, and is arranged a lesser distance from the upright sides of the holder than the diameter of the extinguisher. No lip is therefore provided in this form for holding the front bottom of the extinguisher and dependence is had largely upon the cooperating spring pressure of the top and bottom which press the extinguisher between them and thereby hold it in place. A forward pull on the top of the extinguisher removes it quickly for use.

In Fig. 5, the integral closed lip 55 is provided in place of the lip 21 of Fig. 1, the integral transverse part 56 joining the spaced side elements of the upwardly convex spring bottom 57.

In Fig. 6, a complete loop 60 is made in each side element 61 of the bottom 62 to accentuate the spring action of said bottom. This may more readily be done where the discharge nipple as 63 projects substantially below the bottom of the extinguisher, the loop also serving to protect the extinguisher to some extent.

It will be seen that the type of lip 21 or 55, and the type of top 29 or 45 depends on where the ends of the length of wire are to be arranged, and that the lip may be omitted entirely if desired. In all the forms of the invention shown, there is provided a single length of wire having its end parts clamped together, said length being bent to form comparatively strong top and bottom springs with or without additional holding parts acting by friction, to produce a simple but economical holder preventing movement or vibration of the extinguisher even under highly adverse conditions.

Modifications of the specific structure shown may be made without departing from the spirit of the invention.

I claim:

1. In a holder for fire extinguishers, a one piece length of wire bent to form a pair of similar transversely spaced longitudinal sides arranged symmetrically about the longitudinal center line therebetween, a top and a bottom each having transversely spaced apart side elements projecting forwardly from the respective upper and lower ends of said sides, a pair of parallel transversely spaced members each arranged in a vertical plane and each having a multiplicity of bends joining the respective elements of the top to the corresponding sides, at least one of said bends projecting forwardly to a point forwardly of and below the mid-portion of the top to grip a part of the extinguisher below the top thereof, a pair of bends joining the respective elements of the bottom to the corresponding sides, said top and bottom being resilient and thereby serving as springs to press upon

an extinguisher inserted therebetween, said top having a downwardly extending indent therein yielding upwardly under the pressure of an extinguisher handle forced therewith and moving downwardly under the spring action of the top when the handle has passed the indent, and transverse perforated braces of sheet material joining said sides and each having a flat back for contact with a flat wall, at least one of said braces being arranged in proximity to the ends of the sides.

2. A holder according to claim 1 having an upstanding lip at the front end of the bottom of the holder.

3. A holder according to claim 1 in which each of the bottom elements has a loop therein enhancing the spring action of the bottom.

4. In a holder for fire extinguishers, a one piece length of wire having transversely spaced substantially upright sides, a spring top projecting forwardly of the upper parts of said sides and forming a yieldable continuation thereof, a spring bottom convex upwardly and projecting forwardly of and forming a yieldable continuation of the lower parts of said sides, and braces of sheet material joining said sides at spaced intervals, said braces having perforations therein for the passage therethrough of securing means and having a flat portion rearwardly of the rearmost parts of said sides and securable to a wall to maintain the holder in forward spaced relation to said wall.

5. A holder according to claim 4 having an upstanding lip at the front end of the bottom of the holder.

6. A holder according to claim 4 having an upstanding lip at the front end of the bottom of the holder and having a pair of loops in the bottom intermediate the ends of said bottom.

7. A holder for fire extinguishers comprising a length of wire having a body portion, said por-

tion consisting of two similar side elements in transverse spaced relation and symmetrical about a longitudinal line arranged half way therebetween, parts of said side elements being spaced apart a distance greater than other parts thereof by corresponding sets of bends in said side elements, braces of sheet material wrapped at their end edge portions about said side elements and perforated, the remaining parts of the braces having flat rear faces to bear against a flat wall, one of the braces being arranged adjacent one of the corresponding sets of bends and another of the braces being arranged adjacent another corresponding set of the bends, said bends preventing longitudinal movement of the braces along the side elements, a top portion having two transversely spaced wire elements each forming a forward continuation of one of the side elements, said top portion having a part thereof intermediate its ends and in substantial forward spaced relation to said side elements projecting downwardly from said top portion and adapted to be engaged by the handle of the extinguisher when said extinguisher is moved into and out of the holder, said top being yieldable about its point of connection to the side elements to form a spring, parallel, forwardly bent portions on the side elements and below the top portion each lying in a vertical plane and arranged to engage and frictionally hold an intermediate part of the extinguisher below the top thereof, a bottom portion having two transversely spaced elements each forming a forward continuation of each of the side elements and yieldable about its point of connection thereto to serve as a spring, and a transverse element connecting the spaced elements of the bottom portion, said bottom portion extending forwardly a greater distance than the top portion.

DANIEL KRAKAUER.
